LIQUOR FEED FOR DRUM DRIERS

Charles O. Lavett, Buffalo, N. Y., assignor to Buffalo Foundry & Machine Co., Buffalo, N. Y., a corporation of New York

Application January 8, 1937, Serial No. 119,661

15 Claims. (Cl. 159—11)

This invention relates to a liquor feed for drum driers and more particularly to a mechanism including a liquor feed pipe which is swung back and forth along the valley or space between the two drums of an atmospheric double drum drier for feeding the liquor to be dried thereto.

It is the object of this invention to provide a simple and inexpensive mechanism for distributing the liquor fed to an atmospheric double drum drier along the entire length of the drums by providing a feed mechanism which is reciprocated or oscillated back and forth substantially the full length of the drums, preferably in the manner of a pendulum, so as to distribute the liquor evenly.

Another object is to provide such a feed mechanism which is particularly adapted to feed small quantities of highly concentrated feed liquor along the entire length of the drums of a drier where the drums are of considerable length, uniformly in the dried product not being attainable, under such conditions, where the feed liquor is fed from a stationary distributing manifold.

Another object is to provide such a mechanism in which the liquor may be discharged either in the form of a solid stream or in the form of a spray and in which the feed mechanism can be provided with a plate or the like for stirring, agitating or breaking up the foam of the liquor held between the drums if the nature of the liquor should require agitation or if the liquor should have a tendency to foam.

Another aim is to provide such a pendulum feed mechanism in which the speed and length of the swing of the pendulum feed pipe can be readily adjusted as may be desired.

Another object is to provide such a mechanism which is simple and inexpensive in construction and is reliable in operation.

In the accompanying drawing:

Fig. 1 is an end view, partly in section, showing a conventional double drum atmospheric drier having a hood through which the vapors are vented and equipped with a pendulum feed embodying my invention.

Fig. 2 is a fragmentary side elevation thereof, partly in section.

Fig. 3 is a fragmentary side elevation of the lower end of a modified form of pendulum feed pipe, viewed transversely of the axes of the drums, the same being equipped with a spray nozzle and also with a plate for agitating or breaking up the foam of the liquor held between the drums.

The atmospheric drier in connection with which my invention is intended to be used can be of any suitable construction and is illustrated in

simplified form as composed of a frame 5 having two end heads 6 and 7 in which the opposite ends of the shafts 8 and 9 of the drums 10 and 11 are journaled. The drums are provided with the usual end boards 12 and 13 which confine the liquor in the space or valley 14 between the drums and the drums are illustrated as moving downwardly at their point of closest approach and the dried material scraped off by doctor knives 15, although it will be understood that the drums could rotate in the opposite direction, i. e. upwardly at their point of closest approach. The drums are supplied with steam or other heating medium by any suitable means (not shown) and are rotated from a main drive shaft 18 which drives a large gear 19 on the shaft 8, this last gear meshing with a similar gear (not shown) on the shaft 9 so that the drums 10 and 11 are driven at the same speed.

Supported above the drums is a hood 20 having a reinforced lower rim 21 and tapering inwardly and upwardly to a vent stack 22 of reduced size, the vapors generated on the drums 10 and 11 being drawn upwardly through the hood 20 and vent stack 22 and discharged. On the front and rear walls of the vent stack 22 are mounted bearings 25 in which a horizontal rocking feed pipe 26 is journaled. One end of this feed pipe is connected by a swivel elbow 27 with a liquor feed pipe 28 and the other end of the pipe 26 is plugged or closed, the liquor from the rocking feed pipe 26 being discharged through a depending liquor feed pipe 29, the lower discharge end of which is located in the valley or space 14 between the drums 10 and 11. The liquor feed pipe and particularly its outlet can be of such size as to create no head of liquor in the pipe or the outlet may be confined so as to maintain a pressure in the pipe. The liquor is preferably supplied by means of a variable speed pump (not shown) of such construction as to deliver a constant quantity of liquor. It will also be understood, however, that the liquor may be fed by gravity or any other suitable means. The axis of the rocking feed pipe 26 is at right angles to the axes of the drums 10 and 11 and therefore upon rocking the feed pipe 26 the depending feed pipe 29 is swung along the valley or space between the drums in the manner of a pendulum between the two dotted line positions illustrated in Fig. 2.

To so rock the rocking feed pipe 26 the closed end thereof is provided with a rock lever 30 which is connected by a link 31 with a rock arm 32 fast to a shaft 33. This shaft 33 extends parallel with a rocking feed pipe 26 and is preferably sup-

50

55

- ported by bearings 34 carried by an angle frame 35, the vertical leg of which is supported by the reinforced lower rim 21 of the hood 20 and the horizontal leg of which is supported by the vent stack 22. A second rock arm 36 is secured to the rock shaft 33 and this rock arm is connected by an adjustable rod 37 with a crank 38 on a crank shaft 39. The crank shaft 39 is rotated from the main drive shaft 18 by means of an endless chain 40 passing around a sprocket 41 on the main drive shaft 18 and a sprocket 42 on the crank shaft 39. The speed at which the pendulum feed pipe 26 swings can be adjusted to suit the particular liquor being handled by changing the sprockets 41 and 42. On certain concentrated solutions, three complete cycles per revolution of the drums gave excellent results. The length of the swing of the pendulum feed pipe can be increased or decreased by lengthening or shortening any of the rock arm centers. For this purpose the rock arm 36 is shown as having a series of holes 45 in any of which the pin 46 connecting it to the adjustable link 37 can be inserted to adjust the effective length of the arm 36.
- It will be seen that liquor from the main feed pipe 28 flows through the swivel elbow 27 and rocking feed pipe 26 into the depending feed pipe 29 so that it is discharged from the lower end of the feed pipe 29 directly into the valley or space 14 between the drums of the drier. As the drums are rotated the main drive shaft 18, through the chain 40, drives the crank 38 which, through the adjustable rod 37, reciprocates the arm 36 and rock shaft 33, this reciprocating motion being transmitted through the rock arm 32, link 31 and rock arm 30 to the rocking feed pipe 26. The length of swing so provided is adjusted by selecting one of the holes 45 to attach the rod 37 and is preferably adjusted so that the depending feed pipe 29 swings from the two extreme positions illustrated by dotted lines in Fig. 2 and thereby causes this depending pipe 29 to swing in the manner of a pendulum back and forth between the extremities of the drums and distribute the liquor the full length of the drums.
- Under some conditions it may be desirable to spray the liquor into the trough or valley between the drums. To effect this the modified form of pendulum feed pipe 26a, illustrated in Fig. 3, is provided at its lower end with a spray nozzle 47. With materials requiring agitation or with foaming materials it may also be desirable to provide agitating means at the lower end of the pendulum feed pipe. Such agitating means may take the form of plates 48 suitably secured to the lower end of the pendulum pipe and sweeping through the material held between the drums so as to agitate it and break up any foam.
- The invention has particular application to the distribution of a small quantity of liquor over the entire length of a drum, the length of which is considerable. This has always been a difficult problem, particularly for liquors of heavy concentration. Such liquors do not flow readily and the amount of feed, therefore, could not be easily controlled through a valve and the liquor then distributed to a manifold. With such concentrated liquors, the quantity to be fed to the drums is also comparatively small because generally most of the water has been removed before the liquor is fed to the drums. If this small quantity is fed from a stationary pipe, in contradistinction, to the pendulum feed pipe of the present invention, a variation in the degree of

concentration along the length of the drums occurs. The pendulum feed pipe of the present invention distributes such small quantities of concentrated liquor over the entire length of the drums and therefore largely eliminates such variations in concentration. 5

From the foregoing it will therefore be seen that the present invention provides a very simple and effective means for distributing feed liquor, especially high concentrated feed liquor in small quantities, to an atmospheric double drum drier having drums of considerable length along substantially the full length of the space or valley between the drums and thereby reduces the danger of non-uniformity in the dried product. The feed mechanism is also adaptable for feeding any type of liquor; the liquor can be sprayed or fed as a solid stream; the mechanism is readily adjustable both as to the speed and throw of the pendulum feed arm; and the pendulum feed arm 20 can be used as an agitator to agitate the liquor between the drums or to break up foam.

I claim as my invention:—

1. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, comprising a liquor feed mechanism having a discharge orifice means for continuously discharging the liquid through said orifice, said orifice being arranged to deposit the liquor into the pool between the drums and means for reciprocating said feed mechanism lengthwise of said drums to distribute the feed liquor lengthwise of said pool. 35

2. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, comprising a liquor feed mechanism having a discharge orifice means for continuously discharging the liquid through said orifice, said orifice being arranged to deposit the liquor into the pool between the drums and means for moving said feed mechanism back and forth lengthwise of said drums to reciprocate said orifice substantially the full length of said pool. 50

3. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, 60 comprising a liquor feed mechanism pivotally supported a substantial distance above said drums to swing on an axis disposed at right angles to the axis of said drums and including a depending pipe having a discharge orifice arranged to deposit the liquor into the pool between said drums, means for discharging liquor through said orifice and means for rocking said mechanism to oscillate said pipe along the drums to distribute the feed liquor uniformly along said pool. 70

4. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, comprising a rocking pipe journaled a substantial distance above said drums to swing about an axis at right angles to the axis of said drums, means for supplying liquor to said rocking pipe, a generally vertical pipe depending from said rocking pipe and receiving the liquor therefrom and having an orifice at its lower end arranged to deposit the liquor into the valley between said drums and means for oscillating said rocking pipe to swing the lower end of said vertical pipe and distribute the feed liquor lengthwise of said pool.

5. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, comprising a rocking pipe journaled a substantial distance above said drums to swing about an axis at right angles to the axis of said drums, means at one end of said rocking feed pipe for supplying liquor to said rocking pipe, a generally vertical pipe depending from said rocking pipe and receiving the liquor therefrom and having an orifice at its lower end arranged to deposit the liquor between said drums and means at the opposite end of said rocking feed pipe for oscillating said rocking pipe to swing the lower end of said vertical pipe and distribute the feed liquor lengthwise of said pool.

6. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, comprising a rocking pipe journaled a substantial distance above said drums to swing about an axis at right angles to the axis of said drums, means for supplying liquor to said rocking pipe, a generally vertical pipe depending from said rocking pipe and receiving the liquor therefrom and having an orifice at its lower end arranged to deposit the liquor into the pool between the drums and means for oscillating said rocking pipe to swing the lower end of said vertical pipe and distribute the feed liquor lengthwise of said pool comprising a rock arm on said rocking feed pipe, a crank, and means operatively connecting said rock arm and crank.

7. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley,

8. A double drum drier, comprising a pair of heated drums in close relation to one another, end boards at the ends of said drums to maintain a pool of feed liquor in the valley between the drums, means for rotating the drums in opposite directions whereby a continuous layer of the feed liquor is applied to both of said drums from said pool for substantially the full length thereof, a hood over the drums to cool the vapors generated in the drying operation and means for maintaining said pool, comprising a liquor feed mechanism suspended from said hood and having a discharge orifice, means for continuously discharging the liquid through said orifice, said orifice being arranged to deposit the liquor into the pool between the drums and means for reciprocating said feed mechanism lengthwise of said drums to distribute the feed liquor lengthwise of said pool.

9. A double drum drier, comprising a pair of heated drums in close relation to one another, end boards at the ends of said drums to maintain a pool of feed liquor in the valley between the drums, means for rotating the drums in opposite directions whereby a continuous layer of the feed liquor is applied to both of said drums from said pool for substantially the full length thereof, a hood over the drums to cool the vapors generated in the drying operation and means for maintaining said pool, comprising a rocking pipe journaled in bearings provided in said hood and disposed at right angles to the axis of said drums, a liquor supply pipe, a swivel connection between said supply pipe and said rocking pipe, a pipe hanging from said rocking pipe and receiving liquor therefrom, the lower end of said hanging pipe being open and arranged to deposit the liquor into the pool between the drums and means for rocking said rocking pipe to swing said hanging pipe lengthwise of the drums to distribute the feed liquor lengthwise of said pool.

10. A double drum drier, comprising a pair of heated drums in close relation to one another, end boards at the ends of said drums to maintain a pool of feed liquor in the valley between the drums, means for rotating the drums in opposite directions whereby a continuous layer of the feed liquor is applied to both of said drums from said pool for substantially the full length thereof, a hood over the drums to cool the vapors generated in the drying operation and means for maintaining said pool, comprising a rocking pipe journaled in bearings provided in said hood and disposed at right angles to the axes of said drums, a liquor supply pipe, a swivel connection between said liquor supply pipe and said rocking pipe, a pipe hanging from said rocking pipe and receiving liquor therefrom, the lower end of said

- hanging pipe being disposed in the valley between said drums and having an opening to deposit the liquor into said pool and means for rocking said pipe to swing said hanging pipe lengthwise of the pool to distribute the liquor therealong, comprising a crank rotated by the drive mechanism for said drums, a rock arm fast to said rocking pipe and an adjustable linkage connecting said crank and rock arm.
- 10 11. A liquor feed for a drum drier, comprising a liquor feed mechanism having a discharge orifice arranged to deposit the liquor on the drum, means for reciprocating said feed mechanism lengthwise of said drum to distribute the feed liquor therealong, and means carried by said reciprocating means for agitating the liquor deposited on said drum.
12. A liquor feed for a drum drier, comprising a liquor feed mechanism pivotally supported a substantial distance above said drum to swing on an axis disposed at right angles to the axis of said drum and including a depending pipe having a discharge orifice arranged to deposit the liquor on said drum, means for rocking said mechanism to oscillate said pipe along the drum to distribute the feed liquor uniformly thereto, and means oscillating with said pipe and agitating the liquor deposited on said drum.
13. A liquor feed mechanism for an atmospheric double drum drier, comprising a liquor feed mechanism pivotally supported a substantial distance above said drums to swing on an axis disposed at right angles to the axes of said drums and including a depending feed pipe the lower end of which is disposed in the valley between said drums and is provided with a discharge orifice arranged to deposit the liquor in said valley, means for rocking said mechanism to oscillate said pipe along said valley to distribute the feed liquor uniformly thereto and means oscillating with said pipe and agitating the liquor deposited in said valley.
14. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, comprising a liquor feed mechanism having a discharge orifice means for continuously discharging the liquid through said orifice, said orifice being arranged to spray the liquor into the pool between the drums and means for reciprocating said feed mechanism lengthwise of said drums to distribute the feed liquor lengthwise of said pool.
15. A double drum drier comprising a pair of heated drums in close relation to one another, end boards at the ends of said drums to maintain a pool of feed liquor in the valley between said drums, means for rotating said drums in opposite directions whereby a continuous layer of the feed liquor is applied to both of said drums for substantially the full length thereof and means for maintaining said pool in said valley, comprising a liquor feed mechanism pivotally supported a substantial distance above said drums to swing on an axis disposed at right angles to the axis of said drums and including a depending pipe having a discharge orifice means for continuously discharging the liquid through said orifice, said orifice being arranged to spray the liquor on said drums, and means for rocking said mechanism to oscillate said pipe along the drums to distribute the feed liquor uniformly along said pool.
